DESIGN FOR AN ASH TRAY

Alva L. Duckwall, Jr., Abilene, Kans.

Application October 15, 1946, Serial No. 133,966

Term of patent 3½ years

(Cl. D85—2)

To all whom it may concern:

Be it known that I, Alva L. Duckwall, Jr., a citizen of the United States, residing at Abilene, in the county of Dickinson and State of Kansas, have invented a new, original, and ornamental Design for an Ash Tray, of which the following is a specification, reference being had to the accompanying drawing, forming a part thereof.

Figure 1 is a perspective view of an ash tray, showing my new design,

Figure 2 is a plan view of the same, and

Figure 3 is a central vertical longitudinal sectional view through the same.

I claim:

The ornamental design for an ash tray, substantially as shown.

ALVA L. DUCKWALL, JR.
